PUMP

Augustin J. Syrovy, Detroit, Mich., assignor to
Chrysler Corporation, Highland Park, Mich., a
corporation of Delaware

Application July 5, 1935, Serial No. 29,788

1 Claim. (Cl. 103—162)

This invention relates to pumps and refers more particularly to improvements in pumps adapted to produce and maintain pressure on a fluid, such as oil, suitable for use in systems of motor vehicle transmission control although my improvements are adaptable to a wide variety of applications. As illustrative of one system of transmission control to which my pump is adaptable, reference is made to the co-pending applications Serial No. 724,434 filed May 7, 1934 and Serial No. 752,948 filed November 14, 1934.

One object of my invention is to provide an improved pump which will efficiently and quickly provide a relatively high pressure of the oil, such pressure being maintained preferably without requiring operation of the pump after the required pressure is attained.

Further objects of my invention are to provide a pump having improved characteristics of fluid seal; a pump capable of long and continuous service such as is required in motor vehicle usage, without undue heat generation, noise, wear or failure through other causes.

Another object of my invention is to provide an improved pump having relatively rotating parts for self adjustment whereby wear is minimized, fluid seal is promoted, and manufacture and assembly of the pump parts is facilitated.

A further object of my invention is to provide an improved control of the pressure of the fluid developed by the pump; minimize noise incident to operation of the pump and particularly during the porting events in the cycle of pumping operation; and to provide a compact and novel arrangement of pressure accumulator and control of pressure delivery.

In carrying out the objects of my invention, I preferably employ a pump of the wobble plate type adapted to vary its inclination or "level-off" in response to fluid pressure delivery to automatically maintain a predetermined delivery pressure; also to minimize movement of the pump parts after the fluid has reached its predetermined desired pressure. As a feature of my invention the pump is arranged for maximum delivery to quickly build up its desired pressure, the fluid displacement by the pump then being quickly reduced instead of being gradually reduced as the pressure builds up to the desired maximum.

Further objects and advantages of my invention reside in the novel combination and arrangement of parts more particularly hereinafter described and claimed, reference being had to the accompanying drawings illustrating several em-

bodiments of certain features of my invention and in which:

Fig. 1 is a sectional plan view of my pump assembly taken along line 1—1 of Fig. 2.

Fig. 2 is a side elevational view of the pump assembly, with certain parts in cross section.

Fig. 3 is a sectional view along line 3—3 of Fig. 1.

Fig. 4 is a side elevational view of the right hand end of the pump viewed in Fig. 1.

Fig. 5 is a detail sectional view along line 5—5 of Fig. 1.

Fig. 6 is a detail sectional view along line 6—6 of Fig. 5.

Fig. 7 is a fragmentary view of a pump rotor and port seating element of modified form but adapted for use in the Fig. 1 assembly.

Fig. 8 is a detail sectional view along line 8—8 of Fig. 7.

Referring to the drawings the pump assembly comprises a casing structure A adapted for attachment at openings 10 to a suitable support such as the transmission structure of a motor vehicle (not shown). The casing receives the pump drive shaft 11 journalled at one end in a bearing 12 carried by the casing and supported at the other end in a cylindrical ported base portion 13 of the casing in a manner more particularly hereinafter set forth.

The shaft 11 has a drive gear 14 suitably fixed thereto and adapted to receive power from a suitable source such as a drive shaft of the transmission (not shown). Base 13 has inlet and outlet passages 15 and 16 respectively for the fluid, such as oil, admitted to the pump and delivered therefrom under pressure. The inlet 15 is exposed to a suitable reservoir of oil which has a level above this passage or in suitable communication with a reservoir of oil as may be desired.

Tightly pressed into the cylindrical opening 17 of base 13 is a cylindrical port seat body or ring 18 formed of bronze or other suitable material journalling the adjacent end of shaft 11, this body having inlet and outlet passages 19 and 20 communicating radially at one end with passages 15 and 16 respectively. The other ends of the passages 19 and 20 form circumferentially spaced arcuate inlet and outlet ports 21 and 22 having their adjacent ends terminating in relatively narrow pairs of grooves 23, 24 and 23^a, 24^a. The grooves of each pair taper toward each other (see Fig. 6) and are brought closely together preferably sufficiently so that they are momentarily brought into communication with each

other by the inlet and outlet ports of the pumping cylinders as will presently be apparent.

Surrounding shaft 11 for rotation therewith is the pump rotor B preferably of steel or other suitable material. This body is keyed or otherwise fixed at 25 to shaft 11 and preferably has a clearance with the shaft sufficient to permit the body to slightly shift its position so that the surface at the cylinder head end 26, which is 5 rotatably slidably engaged with the adjacent ported surface of body 18, may accommodate itself to the latter surface. More specifically, in the form illustrated, the body B has a generally cylindrical opening 27 accommodating the shaft 11, this opening tapering from the keyed end of body B, which fits the shaft, to the opposite end. The body B may thus rock about its inner end at key 25 for relatively free movement at the 10 surface of ports 21, 22 whereby the bodies 18 and B are relatively self-adjustable to provide and maintain a good fit preventing leakage, wear, and binding of the parts. Furthermore, when the pump is run-in, a self-lapping action takes place at the rubbing surfaces between bodies 18 and B. 15 The body B has a plurality of circumferentially spaced cylinders 28 opening inwardly toward a wobble or swash plate C, the cylinder head portion 26 having ports 29 for each cylinder. These ports, as body B rotates, successively register with ports 21 and 22 so that they are alternately intake and discharge ports.

Each cylinder 28 slidably receives a piston 30 urged inwardly by a spring 31 into contact with plate C, the inner rounded end 32 of each piston 35 slidably engaging the outer ring 33 of the plate C. This ring is supported by bearing 34 carried by a swinging arm 35 pivotally supported at 36 from casing A. At the other side of shaft 11 the arm 35 is pivotally connected at 37 to an outwardly extending link 38 pivoted at 39 to a lever 40. The lever is pivotally supported at 41 to a projection 42 of the outer closed end of the accumulator cylinder D.

Slidable in cylinder D is a piston 43 urged inwardly by a heavy spring 44, the piston having an outwardly extending rod 45 adapted to engage lever 40 to swing the latter to the dotted position in Fig. 1 for levelling-off the plate C and minimizing or eliminating reciprocation of pistons 30. Piston 43 moves against spring 44 in response to a predetermined desired pressure of the fluid delivered by the pump, the delivery passage 20 being in communication through passage 46 with the accumulator cylinder D at the discharge 47. The oil under pressure is led to a suitable point of usage from cylinder D through the casing passage 48. A cover plate 49 is secured by fasteners 50 to the inner end of the casing A and closes off the inner end of cylinder D and the chamber of auxiliary pump E where such pump is employed.

The pump E comprises a driving gear 51 and driven gear 52 together with oil inlet and outlets 53, 54 respectively, and is adapted to supply oil under a relatively low pressure to lubricate parts of the engine or transmission (not shown).

As the shaft 11 drives rotor B, with plate C positioned as in Fig. 1 for maximum piston stroke, approximately half of pistons 30 are moving inwardly drawing in oil through port 21 and ports 70 29 associated therewith, while the remaining pistons are discharging oil under pressure through their associated ports 29 and outlet port 22 for passage to cylinder D at 47. As each port 28 moves across the face of body 18 between ports 75 22 and 21 thereof to cut-off pressure delivery and

begin suction intake, the pressure delivery as the piston moves to the outward limit of its travel is not abruptly cut-off but such action takes place very gradually as the port 28 progressively moves to include groove 24*. Since groove 24* narrows 5 toward groove 23*, the cut-off is further accentuated in a gradual manner, the port 28 momentarily registering with groove 23* just prior to passage beyond groove 24*. In this manner I have found that a very quiet and efficient pumping 10 action is obtained, free from hydraulic "hammer" and other noises incident to pumping. In passing from intake to pressure delivery between parts 21 and 22, I preferably provide similar grooves 23, 24 for a similar action with each cylinder port 15 29 as will be readily understood.

When the pump is initially operated, the pressure of the oil delivered at 47 to cylinder D rapidly builds up to the desired amount, say 500 pounds per square inch for example, and as this pressure 20 is nearly reached (determined by the value of spring 44) the piston 43 moves outwardly increasing the capacity of cylinder D and moving rod 45 into contact with lever 40. Continued movement swings lever 40 and thereby swings plate C about 25 its pivot 36 into a position approximately transverse to the axis of shaft 11. This levelling-off of plate C progressively lessens the stroke of pistons 30 until they finally are substantially motionless 30 so far as reciprocation is concerned, assuming of course that oil under pressure is not being relieved from the delivery system. Any minor leakages which may be present in the delivery system will require only a small movement of the pistons to maintain the maximum desired oil pressure in 35 the cylinder D.

By normally spacing rod 45 from lever 40, there is provided a lost motion connection between the wobble plate structure and the control therefor and the plate C does not start to level-off as soon 40 as piston 43 begins to move accompanied by further compression of spring 44 so that the maximum stroke of the pistons 30 is realized longer than otherwise. In this manner the maximum pump pressure is rapidly attained. The plate C 45 is, of course, free to assume any position intermediate its inclined position of Fig. 1 and its fully levelled-off position under control of rod 45 according to the demand placed on the delivery system. It will therefore be understood that while 50 the wobble plate C is normally swingable about its pivotal mounting in response to actuation of the control therefor, including the rod 45, this plate is free from such movement and is not actuated when the control member is operated in opposite 55 directions respectively by the fluid pressure within the cylinder D and the spring 44 in taking up and establishing the lost motion connection between the plate 40 and the control therefor.

It should be noted that, in levelling-off, the 60 plate C moves the pistons 30 outwardly to the outer limit of their travel. This is desirable in minimizing air trapping between cylinder head 26 and the outer ends of cylinders 28.

The accumulator cylinder D stores oil under 65 pressure so that when oil is delivered under pressure at passage 48, the spring 44 expands and tends to prevent an otherwise rapid fall of the fluid pressure.

The side-by-side arrangement of my rotor B 70 and cylinder D is important, where an accumulator is employed, since such arrangement makes for a compact assembly and low manufacturing cost; furthermore, I have utilized the accumulator spring 44 also as the load medium control- 75

ling the regulation of the stroke of pistons 38 and consequently controlling regulation of the pump delivery.

Referring now to the modified form of my invention shown in Fig. 7, I have illustrated only a portion of the pump assembly of Fig. 1, it being understood that my Fig. 7 structure may be readily used with the Fig. 1 assembly as will be readily understood. Similar parts are designated by similar reference characters.

In Fig. 7 the body B' does not have a clearance with shaft 11', the relative self-adjusting movement between the face of cylinder head 26' having ports 29' and the face of the non-rotating member 55 having inlet and outlet ports 21, 22 resulting in a self-lapping and sealing action as aforesaid. Thus, the casing part 13 tightly receives the cylindrical body 18' formed with intake and delivery passages 19' and 20' but the adjustable member 55 is now interposed between bodies 18' and B'.

The member 55 is formed with a spherical convex outer face 56 fitting a like concave spherical face of body 18' so that relative adjustment may readily take place between the relatively rotating faces of body B' and member 55. In order to permit the desired small amount of relative movement between body 18' and member 55 and at the same time to prevent member 55 from rotating with body B', a pin 57 is passed through body 18' and enters member 55 (circumferentially spaced from passages 19' and 20') in an opening 58 thereof having a clearance with pin 57.

What I claim is:

In a fluid pump, a supporting structure, a drive shaft journaled in said supporting structure, a rotor drivingly connected to said shaft and having a plurality of cylinders spaced around said shaft and extending in the direction of the axis of rotation of said shaft, pistons reciprocating in said cylinders respectively, a wobble plate pivoted for swinging movement and adapted to actuate said pistons, means for successively supplying fluid to said cylinders and for conducting fluid under pressure therefrom, a cylinder disposed adjacent said rotor and extending in the general direction of said shaft, a wobble plate control piston in said cylinder, means for conducting fluid under pressure from said fluid conducting means to said cylinder for operating said control piston, a spring acting to oppose movement of said control piston by said fluid pressure, a rod secured at one end thereof to said piston and extending through said spring, a lever supported for pivotal movement and lying beyond but in the path of movement of the other end of said rod and constituting a lost motion connection between said control piston and said wobble plate, and a link connecting said lever and wobble plate for swinging said wobble plate in response to movement by said control piston, said lost motion connection accommodating substantial fluid pressure movement of said piston prior to swinging movement of said wobble plate in response to fluid pressure in said cylinder.

AUGUSTIN J. SYROVY.
